UNITED STATES PATENT OFFICE.

GEORGE A. FAIR, OF LOS ANGELES, CALIFORNIA.

COMBINED DOOR OR WINDOW AND VENTILATING STRUCTURE.

1,192,406.

Specification of Letters Patent. Patented July 25, 1916.

Application filed December 18, 1913. Serial No. 807,527.

To all whom it may concern:

Be it known that I, GEORGE A. FAIR, citizen of the United States, residing at Los Angeles, in the county of Los Angeles and State of California, have invented certain new and useful Improvements in Combined Doors or Windows and Ventilating Structures, of which the following is a specification.

10 My invention relates to windows and particularly to metallic windows or doors.

The main or general object of my invention is a construction of this kind which may be used either as a door or window and 15 which is so formed as to provide a hinged sash frame containing sliding main sashes and sliding storm sashes, and in conjunction with which a hinged and removable screen and a hinged and removable guard or grille 20 may be used.

Still another object is to so form the pivoted frame containing the sliding sashes that this frame may be easily removed from pivoted engagement with the window frame 25 itself, and a further object in this connection is to provide the main frame with pivots adapted to be interchanged and to be disposed either at one or the other side of the sash so that the pivoted or hinged frame 30 may be opened at one or the other side as may be desired.

Still another object is to provide locking means whereby the pivoted frame may be locked at either side.

35 Another object of the invention is the provision of means removably supported within the main window frame, constituting a bearing against which the pivoted or hinged sash frame will at all times bear, also constituting the support for the guard and for 40 the screen, and also constituting means for preventing the passage of cold air around the side elements of the pivoted or hinged sash.

45 Generally speaking, I have designed in this combination door and window to secure utility, simplicity and compactness, together with an ability to adjust the window to suit any need, and to adapt it for use in all climates, whether the weather be extremely hot or extremely cold, or whether it be stormy, 50 dusty or fair.

My invention is illustrated in the accompanying drawings wherein:

55 Figure 1 is a perspective view of a window constructed in accordance with my in-

vention, it being understood, however, that the same construction may be applied to a door as will hereafter appear. Fig. 2 is a vertical section from front to rear of the 60 window and window casing shown in Fig. 1. Fig. 3 is a vertical section on the line 3-3 of Fig. 2. Fig. 4 is a transverse section on the line 4-4 of Fig. 2. Fig. 5 is a fragmentary vertical section through the 65 hinged sash frame showing one of the sliding sashes as supported by a counterweight. Fig. 6 is a fragmentary vertical section of the upper portion of one of the side bars of the hinged or pivoted sash frame showing 70 the means whereby the upper pintle is rotatably supported in the main window frame. Fig. 7 is a fragmentary horizontal section enlarged to about natural size showing the details of construction of the hinged window frame and of the sliding sashes mounted 75 therein. Fig. 8 is a fragmentary horizontal sectional view through the pivoted or hinged window casing to show the means for locking the window casing to the window frame to prevent any opening movement thereof. Fig. 9 is a fragmentary front elevation of the left hand side of Fig. 12 showing the locking bolt and the means whereby it is held retracted. Fig. 10 is a 80 perspective view of one of the catches for the sliding windows. Fig. 11 is a fragmentary vertical section view through the hinged window frame and one of the sliding sashes showing the action of the latching means 85 illustrated in Fig. 10.

Corresponding and like parts are referred to in the following description and indicated in all the views of the accompanying drawings by the same reference characters.

95 Referring now particularly to Figs. 1, 2 and 4, it will be seen that the window or door casing within which the sliding and pivoted sash frames are mounted as heretofore stated, is of sheet metal. This casing 100 is designated 2 and is rectangular in form and extends entirely through the window opening. Preferably this casing 2 is so formed that the sides, bottom and top of the frame are flat or straight without any projecting corners, shoulders or other protuberances so that it may be inserted into the window opening without difficulty.

105 Bolted or riveted, but preferably bolted, to the sheet metal frame 2 at the sides thereof are the T irons 3, each formed with an outwardly projecting median web 4. When

the window frame is to be applied to a building in the course of construction, it is preferable to attach these T irons 3 to the casing 2 and to provide the projecting webs or flanges 4 so that the blocks, stones or bricks from which the building is made may be built in on each side of these webs or flanges to thus hold the window frame securely in place. Where, however, the window frame 5 is intended to be inserted in a window opening in a building already constructed, these T irons 3 are removed. The T irons are held to the frame by means of bolts or screws 5, and when the T irons are removed, screws 10 may be applied through the openings provided in the frame 2 to receive these bolts 5 and the casing screwed to the ordinary window frame or to the wall structure.

Formed as part of the frame 2, and preferably formed of sheet metal and disposed at the top of the frame and at the bottom thereof so as to constitute the lintel and sill of the window frame, are the ventilating boxes 6 and 7, the box 6 being at the upper end of 20 the window frame and the box 7 at the lower end thereof. These boxes are hollow and are provided, as will be later described, with means whereby fresh air may be directed into and through the box and whereby the 25 discharge of fresh air into the room may be controlled.

Disposed against the sides of the window frame 2 and bolted, screwed or otherwise detachably attached thereto are the vertical 30 hollow members 8. The inner edges of these members are concavely rounded as at 9 for contact with the rounded faces of side rails 10 and 11 forming the side rails or bars of a pivoted sash frame.

40 The window or door frame comprises rectangular frame members 12 disposed in spaced relation to each other and held in such spaced relation by vertical transverse plates 13, which are detachably bolted to the members 12, each of the plates 13 being formed at its edges with flanges 14 through which the bolts or screws 15 pass, and by the upper and lower bars or rails of the frame. Closing the opposite sides of the 45 frame bars formed by the members 12 and 13 are the vertically disposed, outwardly rounded or convex plates 16 which are detachably attached to the margins of the members 12 by means of the screws or bolts 17. The space 18 defined by the plate 16, the members 12 and the transverse web 13 constitutes ordinarily a weight containing chamber. The upper and lower ends of this 50 chamber 18 are closed by prolongations of the upper and lower frame bars 19 and 20, these upper and lower frame bars 19 and 20 being of sheet metal construction preferably hollow for the sake of lightness.

The upper and lower ends of each of the 55 side bars formed by the members 12, 13 and

16 are provided with the pintles as shown clearly in Figs. 3, 6 and 7. The lower pintle 22 as illustrated clearly in Fig. 3 is provided with a base and is bolted to the continuation of the lower plate 20^a of the lower frame bar 70 and rests in a socket 23 formed in the upper plate or wall of the lower ventilating chamber 7. As illustrated in Fig. 6, the upper end of each side bar of the window is provided with a pintle 24 which is attached to 75 the upper plate 21 which closes the upper end of each of the compartments or chambers 18, whereas for the reception of the lower pintles the upper wall of the lower ventilating chamber or casing was formed 80 with sockets for the reception of the upper pintles. The lower wall of the upper ventilating compartment or chamber 6 is formed with a recess 25 extending inward from the interior face of the window frame 85 and each recess is filled with a block 26 having a half bearing 27 formed at its inner end which normally bears against the pintle 24 as illustrated clearly in Fig. 6. The block 26 has such snug engagement in the recess 90 25 as will prevent its easy removal after the block is inserted, or this block may be locked in place in any suitable manner as by a screw or bolt 28 passing through a flange formed upon the block and into the wall of the 95 upper ventilator casing 6. When the block 26 is removed it is an easy matter to tilt the pivoted frame forward and then withdraw the lower pintle from its socket.

It will of course be understood that only 100 one pair of pintles is in actual use at one time, that is, an upper pintle and a lower pintle, but that both of the side bars of the pivoted sash frame are formed alike so as to permit the pintles to be shifted from the 105 left hand side of the window frame to the right hand side thereof if desired to thus change the direction of opening of the window to adapt it to any desired circumstances of house construction. This transposition of the pintles may be easily accomplished by removing the locking blocks 26 whereby the window may be readily withdrawn, then detaching the plates 16, removing the upper pintle and lower pintle 110 115 and reapplying them on the opposite side of the window, after which the plates 16 are replaced and the pintles inserted in their proper sockets and the locking blocks 26 again put in position. This is an important 120 feature of my invention as it permits the window to be easily changed from a left hand opening window to a right hand opening window, or vice versa.

It will be noted that the plates 16 are 125 curved concentrically to the pintles 21 and 24 and that the inner edges of the members 8 are also curved to conform to the curvature of the plates 16 so that the plates 16 always bear against these members or plates 130

8, whether the window be open or closed, or in a position midway between the fully opened or closed positions. Thus the curved inner face of the side rail or bar on the 5 pivotal side of the window always has an air-tight and water-tight engagement with the member 8 and this prevents the passage of air between the hinged side of the window and the window casing proper. In 10 almost all windows known to me where a frame is hinged to a window casing, there is more or less space between the hinged frame and the casing through which air will pass and there is much difficulty found 15 in weather stripping this space to prevent the ingress of cold air.

Mounted within the frame formed by the rectangular members 12, the webs 13 and the plate 16, and between the upper and lower 20 bars 19 and 20 of the window are a plurality of sliding sashes. Preferably there are two pair of these sashes, one pair being disposed like the sashes of an ordinary window adjacent the inner face of the swinging 25 frame and forming ordinary upper and lower window sashes, the other pair being disposed adjacent the exterior of the swinging frame and forming sliding storm sashes. All of these sashes are constructed in the 30 same manner and are mounted in the hinged or pivoted frame for sliding movement as will be now described.

By reference to Figs. 2 and 7, it will be seen that each sash comprises a glass pane 35 29 (or 29^a) supported between rectangular frames 30 of light sheet metal. These rectangular frames are wide enough to project beyond the edge of the glass pane on all sides and they are spaced from each other 40 by means of spacing strips 31 which extend around the four sides of the frame and which are disposed against the edge of the pane.

Rubber packing or other suitable cushioning material may be placed between the strips 31 and the pane. The strips forming the frame 30 project beyond the spacing strips 31 as illustrated clearly in Fig. 7 so as 45 to provide parallel members embracing guide stops 35 which are detachably connected to the web 13 by means of screws 36 or in any other suitable manner. A parting bead 37 is disposed between the two pair 50 of sashes and is held in place by means of screws 38 or in any other suitable manner.

As before remarked, there are two pair of sashes. The pair designated 29 are designed as ordinary window sashes, while those designated 29^a are designed for use 55 as storm sashes. There is an upper and a lower sash to each pair, and it will be obvious that when one of the sashes of each pair is shifted to its uppermost position and the other sash shifted to its lowermost 60 position, the window opening will be en-

tirely closed, but that both of the lower sashes may be raised and both of the upper sashes may be lowered, or that both of the upper sashes may be lowered partly and both of the lower sashes raised partly so 70 that air can enter both at the top and bottom of the window. It is also to be noted at this point that when the outer pair of sashes is closed and the inner pair of sashes is closed, a dead air space is provided between the sashes which will prevent the dissipation of heat in the room and prevent the cold air outside from affecting the temperature of the room. The upper and lower hollow bars of the hinged or swinging frame 75 39 forming horizontally extending continuations of the guides 35. These members 39 receive the lower and upper ends respectively of the sliding sashes and fit sufficiently snug to prevent the jarring or rattling of the sashes, and also prevent the ingress of cold air either above or below the sashes.

In order to prevent the ingress of cold 90 air at the upper and lower ends of the swinging sash frame, I form the upper and lower members 19 and 20 thereof each with a longitudinally extending depression 40 formed in the metal of these members, and 95 also form in the upper and lower ventilator casings 6 and 7, the longitudinally extending chambers 41, within each of which is disposed a longitudinally extending weather strip 42 forced outward, that is, toward the 100 swinging window frame by springs 43, each of these springs surrounding a pin 44. The outer edge face of each weather strip is beveled so that it will not impede the swinging movement of the window but so that each 105 weather strip will be forced inward as the window swings outward or inward and then forced outward when each recess 40 comes in alinement with the weather strip. The strips 42 may be made of felt, leather, wood or 110 any other suitable material and act not only as weather strips but also to prevent any rattling of the hinged or swinging frame.

The sashes of each pair of sashes may be counterbalanced either by counterbalancing 115 one sash by the other sash of the pair, or by the use of the usual counterbalancing weights moving in the vertical chamber 18. To this end I mount within the hollow swinging frame the pairs of pulleys 45 as shown 120 clearly in Figs. 2 and 3. There are a pair of pulleys for each end of each pair of sashes, each pair being mounted in a yoke swiveled or otherwise rotatably connected to the upper wall of the swinging frame. When one 125 window sash of a pair is used to balance the other window sash of the pair, the sash cord 46 as illustrated on the right hand side of Fig. 2 and in Fig. 3 passes over one of the pulleys of the pair and its ends are connect- 130

ed, one end to the lower sash and the other end to the upper sash. Thus when the upper sash is pulled down, the lower sash will be raised, and when the lower sash is pulled down the upper sash will be raised. Where, however, the sashes are to be connected to weights, the pair of pulleys is turned at right angles to the position shown in Fig. 3, that is, to the position shown on the left hand side of Fig. 2 and two cords are used, one running from each sash to a weight 46. If desired, the counterweights 46 may be left within the chamber 18 with the cords passing up and over an eye 47 and ready to be passed through the pulleys and attached to the window sashes. It will be understood, of course, that where counterweights are used, there will be as many counterweights as there are sashes. It will also be understood that when it is desired to attach the counterweights to the window sashes, it is only necessary to remove the swinging window frame, take out the plate 16 and the web 18 and then attach the proper cords to the proper sashes, after which the parts are replaced and the swinging frame is again put in position.

In order to hold the sliding inner sashes in any adjusted position, I perforate the vertical bars of the frames 30 of said sashes as at 48, as shown clearly in Figs. 10 and 11, and provide a spring latch 49 mounted upon one or both of the vertical bars of the swinging frame, this spring latch having an inwardly projecting pin 50 extending through a perforation in the said vertical bar of the swinging frame and engaging in any one of the perforations 48. These perforations 48 are arranged in a vertical series so that the sliding sash may be adjusted to any degree required. It will of course be understood that the same latching device may be used for both the upper and lower sashes and for the outer or inner sashes. Preferably the pin 50 is rotatably mounted within the spring 49 and is provided with a laterally projecting finger or lug 51. The perforation 51^a through the side bar of the swinging window frame has the form of a keyhole slot. When the pin 50 is turned in one direction, the lug 51 will engage with the face of the window and prevent the spring from forcing the detent pin inward. When, however, the lug is turned into alignment with the keyhole slot, the pin will be forced inward and into engagement with the perforation of the sash frame, thus supporting the sash frame as heretofore described. Preferably the swinging frame is also provided with inwardly projecting detachable shade brackets 52 adapted to support a spring roller shade 53, and the swinging frame may also be provided with the detachable curtain supports 54 if so desired for the support of portières or draperies. Detachable shade

brackets 55 may also be provided as illustrated in Fig. 2 at the middle of the swinging window or door frame for the purpose of supporting shades controlling the passage of light through the lower portion of the window or door frame. In order to prevent the collection of water upon the lower bar 20 of the swinging frame between the outer and inner plates 12, I form drainage perforations 56 in the outermost one of these plates so as to allow the water to drain outward.

Disposed outward of the swinging frame containing and supporting the sliding sashes as heretofore described, is the screen frame 57 which is rectangular in form and carries a screen of fine wire netting or other suitable material. This screen frame is hinged as at 58 to one of the filling plates 8. It is obvious, of course, that if the pivotal point of the hinged window or door frame be transposed, the hinged connection of the screen frame may also be transposed. The free edge of the screen frame is formed with one or more perforations 59 through which a bolt, screw or other locking device may pass into the adjacent member 8 so as to hold the screen firmly in place and yet permit the screen to be opened inward when desired.

Mounted outward of the screen frame 56 is the guard 60 or grille which is a rectangular metal frame carrying bars, this guard 60 being hinged at one edge to one of the members 8 as shown clearly in Fig. 4. Here again it may be stated that the hinges of this guard may be transposed so as to suit any transposition of the pivotal point of the sash carrying frame. The guard is held closed by means of any suitable bolt 61 or other locking device.

The uppermost transversely extending plate of the window or door casing 2 is outwardly extended as shown in Fig. 2 and formed with the downwardly depending hood 2^a. Mounted beneath this hood is a spring actuated roller 62 upon which is mounted an awning 63. The lower end of the web 63 forming the awning is provided with a transverse bar 64 which moves in a channel or guideway 65 formed in the vertical frame members 2 of the window or door frame. This channel 65 is formed at a plurality of points with inwardly and upwardly extending extensions 66 within which the ends of the rod 64 may rest. By drawing the awning down and then drawing the rod rearward with its ends in engagement with either one of the extensions 66, the awning may be held at any suitable point. When the awning is raised, it is entirely housed by the hood 2^a and protected from the weather and from the collection of dirt and dust. The awning may be drawn down so as to entirely conceal the

window, or it may be raised to its full height or partially raised.

The upper and lower ventilating casings 6 and 7 each has at its outer side the outwardly and downwardly projecting hood 67 and the inlet opening of the casing is protected by a screen of perforated or reticulated metal designated 68. The outlet opening 69 of each of these ventilating casings 10 is covered by wire gauze or perforated metal and is controlled by means of a damper plate 70 pivotally mounted at its lower edge upon the lower wall of the opening 69, and this damper plate is provided with arcuate 15 wings 71 at opposite ends having a height equal to the opening 69. The front of the damper plate is provided with a handle or hook 72 whereby the plate may be manipulated. A dust-tight joint is formed between 20 the damper plate and the lower wall of the opening which at all times and in any position of the damper 70 prevents the inlet of dust through the joint. Furthermore, this bearing being continuous across the whole 25 length of the damper plate prevents the middle of the damper plate from bending when the damper plate is pushed in and thus binding on its pivots which it would do if the pivotal support of the damper plate 30 were only adjacent the ends of the plate. Stops are, of course, provided to limit the outward movement of the damper plate, and the damper plate itself constitutes a stop limiting the inward movement of the damper plate flush with the face of the ventilator casing.

In order to provide means for heating the air which may enter through the lower ventilator as it passes into the room, I preferably extend the lower plate of the main frame 2 so as to form a depending screen designated 76 within which a radiator 77 is disposed. This screen may be either imperforate or provided with grille work or 45 like open work structure to permit the passage of the hot air from the interior of the box to the exterior thereof. The lower ventilator 7 discharges at a point directly above the casing 76 and as a consequence the cold 50 air from this ventilator is warmed as it enters the room. As illustrated in Fig. 1 where this heater is arranged in a house, the casing 77 should be set in the wall of the house so that the radiator will be entirely 55 concealed and the casing will not project out into the room.

While I may use any suitable devices for holding the swinging door frame or window frame closed, I preferably provide for this 60 purpose the bolts illustrated in Figs. 8 and 9 and also shown in Fig. 4. To this end the plates 16 are each perforated for the passage of a bolt 78 which when projected is adapted to enter a perforation in the casing 2. This bolt is suitably guided in its

movement and is provided at its inner end with an outwardly projecting pin 79 extending into a slot 80 formed in the face plate 12. The stud or pin 79 is annular in cross section and interiorly threaded for the reception of a headed screw 81. It will, of course, be obvious that when the window is pivoted at its left hand side to the window frame, the bolt 78 on the left hand side will not be used, but that the bolt 78 on the right hand side will be used, and that when the window frame or door frame is pivoted upon the right hand side, the bolt on the left hand side of the frame will be used. Therefore, one of these bolts will be 80 idle while the other will be capable of being retracted or projected. It is for this reason that I provide the detachable headed screw 81 which may be shifted from one bolt to the other so that the bolt on the hinged 85 side of the frame when retracted can not be projected. As a further means for preventing the projection of the bolt, I form the slot 80 at its inner end with a downwardly extending recess 80^a in which the pin 79 will 90 rest and catch when the bolt is retracted. The bolt must therefore be rotated so as to lift the pin 77 out of this notch 80^a before the bolt can be shot.

It will be seen from Fig. 1 that if it is 95 desired that the whole area of the window opening shall be unobstructed so as to permit the free ingress of fresh air, the swinging frame may be swung upon its pivots in the position shown in Fig. 1. If, however, 100 it is desired to still further provide for the inlet of fresh air, a fan may be placed upon the window casing or otherwise suitably supported adjacent to the window opening so as to positively draw in the fresh air and 105 force it into the room. Even if the window is closed, this fan may be used in connection with the upper ventilator. For the purpose of attaching this fan, I intend to form the window casing, or provide the wall immediately adjacent the window casing, with 110 perforations 102 whereby the screws for holding the base of the fan may be inserted in the wall or withdrawn therefrom. While I do not wish to limit myself to any particular manner of constructing the casing 2 upon which the sash structure is mounted and with which it forms a unitary part, I have preferably made this casing of sheet metal and braced at the corners by means of 115 angle irons 103 as shown clearly in Fig. 3.

While I have heretofore described my invention as being applied to a window, I wish it thoroughly understood that practically the same construction may be used 120 as a door, the proportions being however changed, and that as a door the structure will have the same advantages and utility that it has as a window. My construction is particularly adapted for the doors and 125 130

windows of bungalows, but it may be equally well applied to office buildings and houses and is also very well adapted to be used for forming the doors or windows of railway cars, street cars, steamships and like structures, and because of its lightness these doors and windows are adapted to be used in such structures as Zeppelin airships where lightness is a vital matter. Furthermore where my construction is used in a door or window, there is no necessity of a transom over the door or window for the purpose of letting in air or ventilating, and this is particularly true where the structure is used upon ships or upon railway trains.

My improved window or door combines a maximum of utility with great simplicity. It is exceedingly compact and yet is adapted to a large variety of conditions and needs. Because of the manner in which the ingress of air may be controlled or entirely prevented, it is adapted to be used under all climatic conditions. As nearly all of the parts of the window are metallic, it is entirely fireproof and its construction is such that it is relatively light and easily handled. The sashes are so simply formed that very little material engages the glass panes and thus the window panes themselves are only very slightly obstructed. The sashes may be readily removed and replaced at any time and as readily connected to weights or to each other as previously explained. The swinging frame which forms the main frame of the door or window as the case may be, may be pivoted either on one side or the other as the exigencies of any particular case may necessitate and this change may be made at any time. The inlet of air around the window or door frame, that is, around the main frame of the structure is entirely prevented by the members 8 and by the weather strips 42. These weather strips 42 further act to prevent any rattling of the sashes in their sash channels.

By providing two sets of sashes a dead air space may be easily provided in winter which will insulate the interior from the exterior air, and in summer these sashes may be opened at top, at bottom or at both ends, or the entire window opening may be disclosed by swinging the main window frame or door frame inward.

Another important feature of my invention is that the storm windows, that is, the two outside sashes, are incased in the same door or window frame as the main sashes, thus doing away with the necessity, bother and expense of removing the storm sashes in the spring and then replacing them in the autumn. These storm windows or sashes are adjustable like the inside windows to any degree and have also like the inside sashes, two kinds of movement, that is, one a swinging movement with the swinging

frame, and the other the usual vertical movement. Furthermore, both the outside and inside sashes may be either counterbalanced by each other or by weights.

A special and particular advantage of my construction lies in the thinness and compactness of the structure. With this construction I can if desired place all four sashes, that is, the ordinary pair of sashes and the pair of storm sashes with a parting strip between them, a screen and grille work, within a space of not more than two inches thick. Thus this door or window construction is particularly adapted for street cars and other vehicles. Furthermore, this provides for a maximum of sill space and permits the window casing to be of a very slight depth. In bungalows and like structures where floor area is of importance, this feature is of considerable advantage.

A special feature of my invention as far as its appearance goes, lies in the fact that the means whereby the swinging frame is hinged is not observable. In most if not all metal door frames and window frames, the hinge is attached to the surface of the frame without even being countersunk, thus giving the frame a heavy and inelegant appearance. The hinge whereby my swinging frame is pivotally mounted upon the casing is concealed and can not be seen until the door is taken down, the pivot being entirely out of sight.

A further advantage secured by my window is that by removing the projecting rib or tongue 4, the window casing may be screwed directly to the ordinary window casing or framing of a building already constructed, and that the window frame is equally adaptable to buildings in course of construction where the ribs or tongues 4 will securely hold the frame from any movement, and further act to prevent the inlet of air around the joint between the casing and the wall.

It will be observed that my window structure is a unitary combination of window frame, window sashes and a hinged window sash frame, together with an awning, a grille and a screen adapted to be inserted in place and removed as a unitary structure, and further that all the necessities which may arise as regards ventilation of air and the protection of property within a room have been provided for in my improved structure.

What I claim is:

1. A structure having a window opening, a window frame fitted in said opening and having a hollow lintel and a hollow sill and provided with pivot-receiving recesses in said lintel and sill, a hollow sash frame fitting within the window frame, pivots detachably mounted in the upper and lower

ends of the sash frame adjacent one side of said frame to engage the pivot-receiving recesses in the window frame, a pivot-retaining block removably fitted in one of said recesses against the pivot therein, and fastening devices mounted in the sash frame at the sides thereof to engage the sides of the window frame.

2. A frame for a window opening consisting of inner and outer plates forming open frames, webs secured to and extending transversely between said plates intermediate the inner and outer edges thereof, transverse plates connecting the outer edges of said

inner and outer plates, the plates connecting the vertical side edges of the inner and outer plates being arcuate, pivots at the upper and lower ends of the open frames concentric with the arcuate plates, and sash guides on the inner face of the transverse vertical webs.

In testimony whereof I affix my signature in presence of two witnesses.

GEORGE A. FAIR. [L.S.]
